OF ONE-HALF TO NICOLAI ALEXEEFF, OF MOSCOW, UNION OF SOCIALIST SOVIET
REPUBLICS

PROCESS FOR THE WET SPINNING OF FLAX, HEMP, AND OTHER TEXTILE FIBERS

No Drawing. Application filed May 20, 1927, Serial No. 193,074, and in Union of Socialist Soviet Republics December 21, 1926.

A process for the wet spinning of flax, hemp and other textile fibers is known, in which the wet spinning is facilitated by introducing into the water substances capable of forming an emulsion and of increasing the moistening capacity of the water, thus rendering it possible to work at considerably lower temperatures and even without pre-heating as is otherwise usual. Such substances are sulphonated acids obtained by the sulphonating of fats, high molecular sulpho-aromatic fatty acids, as well as salts of all these aromatic acids.

According to the present invention it is possible to use for increasing the moistening capacity of the water, not only the acids and salts referred to above, but also their free acids and other salts and corresponding acids, viz. sulphonic acids of the aromatic compounds with or without hydrocarbon side chains, sulphonic acids of hydrogenated aromatic hydrocarbons or their derivatives such as for instance octo-hydroanthracene sulphonic acid, naphtha sulphonic acids, or fatty aromatic acids, sulphonic acids of other hydrocarbons and their derivatives and especially sulphonic acids, which are obtained by the sulphonation of aromatic, hydro-aromatic or naphtha hydrocarbons in the presence of some alcohols, such as for example propyl, butyl, isopropyl alcohol or the like, or finally various salts of all the said acids and also solutions of the fatty acids in the alcohols.

In addition according to the present invention the same purpose can also be served by sulphonated distillates of coal-tar, naphtha tar or shale tar, sulphonated hydrocarbons or derivatives of the same, sulphonated glycerides and sulphonated fatty acids, as well as emulsions, solutions and mixtures of these substances, and of the above mentioned acids and salts with terpenes, aromatic or hydro-aromatic hydrocarbons or their derivatives, such as for instance phenols or cresols, as well as with fatty acids, such as for instance acetic acid, formic acid or with the alcohols dissolved in water.

When very small proportions by weight of these substances are introduced into the

moistening water (in many cases 0.05% is sufficient) the yarn obtained is considerably more uniform, cleaner and lighter.

Experiments have also shown that by adding the said substances to the water, it is possible to reduce more or less the requisite temperature of the liquid according to the nature of the fibers to be treated and the properties of the added reagents. For instance by adding 0.05% of neutralized "Kontakt" (naphtha-sulphonic acids) the wet spinning can be carried out at an ordinary temperature (about 15-20° C.) that is to say without pre-heating.

At the same time it is possible to work either with ordinary wet spinning machines or the slubbing may for instance be moistened first of all on the bobbins and spinning continued without passing through the water.

The reduction of the temperature for wet spinning to room temperature dispenses with the necessity of steam pipes, as well as the attendance on the latter and eliminates all the difficulties and detrimental effects involved in spinning with hot water.

The reduction of the temperature in most cases also increases the strength of the yarn.

The addition of the said reagents to the water also has other advantages, insofar as during the wetting of the yarn, some of the impurities in the same are washed out as a result of the good washing capacity of the reagents, and the spun thread is much cleaner and whiter.

Moreover the pectins, shive, fats and other impurities remaining in the fibers after spinning, after a wet spinning process of the above kind are more readily attacked by alkalies in the subsequent bucking process and the finished product is cleaner and whiter than has hitherto been the case, the dyeing of the same also being considerably facilitated.

The addition of the said reagents in wet spinning also accelerates the subsequent processes and in addition to economizing in time, consumption of steam, lyes and the like, also reduces the loss in strength of the product during further treatment.

The phrase "increasing the moistening ca-

capacity of the water" as occurring in the claims is to be understood to imply the imparting to the ordinary technical hard water the capacity of a quicker penetration of fibrous materials and a better removal therefrom of water-soluble substances. The substances, which impart to the technical water the capacity of quickly penetrating fibrous material and extracting soluble substances therefrom, are 10 sulfo-acids and their salts which are indicated in the application.

Having now particularly described and ascertained the nature of my said invention and in what manner the same is to be performed, 15 I declare that what I claim is:—

1. In the wet spinning of textile fibers the method of increasing the moistening capacity of the water which comprises adding to the water a very small amount of an aromatic 20 sulphonic acid having a mean molecular weight not over 350.

2. In the wet spinning of textile fibers the method of increasing the moistening capacity of the water which comprises adding to the 25 water a very small amount of a naphthalene sulphonic acid having a mean molecular weight not over 350.

3. In the process of wet spinning textile fibers, the step which comprises subjecting 30 the fibers to the action of an aqueous medium containing a small amount of an aromatic sulphonic acid and its salts having a mean molecular weight not over 350 to facilitate the wetting action of the water.

35 4. In the process of wet spinning textile fibers, the step which comprises subjecting the fibers to the action of an aqueous medium containing a small amount of a naphthalene sulphonic acid having a mean molecular weight 40 not over 350 to facilitate the wetting action of the water.

In testimony whereof I affix my signature.
GRIGORI PETROFF.
